SANDPAPER HOLDER AND MANIPULATOR

Tyler K. Lovejoy, Hastings, Minn., assignor to
 Lovejoy Products, Inc., Hastings, Minn., a corporation of Minnesota

Application September 24, 1948, Serial No. 50,917

5 Claims. (Cl. 51—187)

1

This invention relates to devices for holding and manually employing sandpaper and other sheet abrasives.

Sandpaper blocks and holders of various forms have been utilized to reinforce and distend a strip of sandpaper or the like and some have had provision for attachment of the sandpaper to the block or frame to restrict slippage and wear of the abrasive sheet. Such devices, to my knowledge, have been for the most part, cumbersome or inefficient, or have required time and effort in the application of the abrasive sheet thereto. Many thereof while furnishing means of attachment of a sandpaper strip to a supporting block, have permitted the sandpaper with use, to become slack in its wrapped position around the corners of the holder, thereby materially reducing efficiency and quickly wearing off the abrasive at the slack portions of the sandpaper strip.

It is an object of my invention to provide a simple, inexpensive but highly efficient sandpaper holder and manipulator which through simple snap action connection means between a pair of clamping blocks, enables a strip of sheet abrasive to be readily installed or removed and which furnishes positive clamping action against the turned ends of a sandpaper strip to positively retain the strip flush against the manipulating block and to prevent slack in the strip during use of the device.

Another object is the provision of a two-part sandpaper block comprising a pair of superimposed blocks or plates connected together by a simple mechanism which when extended by forcing the blocks apart longitudinally, shifts the relation of the blocks to facilitate application of a strip of sheet abrasive to the outer surface of one of said blocks with wrapping about the ends of said blocks and which further, through snap action of the connection mechanism and resilient means, forces the opposing clamping surfaces of said blocks together to tightly retain the ends of the abrasive strip.

These and other objects and advantages of my invention will more fully appear from the following description made in connection with the accompanying drawings wherein like reference characters refer to similar parts throughout the several views and in which:

Fig. 1 is a perspective view of an embodiment of my invention with a strip of sandpaper applied thereto for use upon a surface to be abraded;

Fig. 2 is a longitudinal section taken on the line 2—2 of Fig. 1;

Fig. 3 is a similar longitudinal section showing

2

the blocks spaced apart for removal or application of a strip of sheet abrasive thereto, the dotted lines indicating a tilted position of the upper block to facilitate connection of one end of the strip with the lower block;

Fig. 4 is a horizontal section taken on the line 4—4 of Fig. 3;

Fig. 5 is a cross section taken on the line 5—5 of Fig. 3; and

Fig. 6 is a side elevation showing a somewhat different form of my invention adapted for manually employing an abrasive sheet upon a fragile article.

In both forms of the invention illustrated, I provide a pair of substantially similar cooperating, rectangular blocks indicated as entirées by the numerals 8 and 9, the upper block 8 preferably being rounded at its edges for comfort of the user. Both blocks as shown, are provided with rectangular central recesses 8a and 9a respectively in the opposing faces thereof in which the attachment portions of a peculiar connecting link are adapted to be seated and countersunk. The remainder of the opposed or inner faces of blocks 8 and 9 are preferably planar and provide opposed clamping portions 8b and 9b adjacent the ends thereof. The blocks may be constructed of any suitable rigid or semi-rigid material such as wood, fiber composition, plastic or rubber, or metal.

The lower block 9 as shown, is provided with a prong-carrying plate which conforms generally to the lower recess 9a and is preferably somewhat shorter than said recess, said plate having upturned terminal portions providing sharpened prongs 10a which are adapted to pierce the ends of a strip of sandpaper or other flexible sheet abrasive S which is wrapped snugly about the outer or lower face of block 9 with its ends folded closely against the ends and corners of block 9.

The two cooperating blocks 8 and 9 are connected together to provide clamping pressure therebetween against the turned ends of the sandpaper strip and further to provide spaced relation between the blocks to facilitate attachment and removal of a strip of flexible sheet abrasive.

My novel connection mechanism as shown, comprises a toggle link 11 in the form of a flat plate adapted to be snugly collapsed in parallel relationship to the opposed faces of the blocks within recesses 8a and 9a, said toggle link having laterally extending flat hinge pintles 11a at both ends thereof. The pintles 11a are of elongated, oblong cross section to cooperate with the curved

resilient fingers 12a and 13a of upper and lower attachment plates 12 and 13 respectively. Plates 12 and 13 have flat attachment portions centrally apertured as shown, to receive a securing element such as a nutted bolt 14. The head of each of the bolts used is preferably countersunk in the outer surface of the respective block and the nut 14a is applied to the inner end thereof and in the case of lower attachment plate 13, also passes through the prong-carrying plate 10 to anchor the same in operative position. The attachment plates 12 and 13 are identically formed although reversed in position in their application to the two blocks 8 and 9. They are preferably formed, each from an integral rectangular piece of somewhat resilient material, as shown, the piece being slit from one end thereof along parallel lines longitudinally of the piece to form a central tab 12b or 13b as the case may be and to provide the curved resilient fingers 12a and 13a respectively. Said fingers are convexly curved to extend somewhat above the attachment surface of the respective pieces or plates and are sprung outwardly from the attachment portions when the flat hinge pintles of the toggle link 11 are swung from the collapsed position of link plate 11 to the erect position shown in Fig. 3, being tensioned by such swinging and exerting a snap action dead center principle upon the pintles and the link 11 when the blocks 8 and 9 are pushed together from the position shown in Fig. 3.

My novel connection mechanism for the co-operating clamping blocks utilizes therefore, a linkage structure having terminal portions which are hingedly connected to the respective blocks 8 and 9 along parallel axes transverse of the blocks and provides for spacing of the blocks as shown in Fig. 3, to apply or replace the abrasive strip. It will further be noted that due to the specific form of connection, the overlying relationship of the blocks is shifted longitudinally, as shown in Figs. 2 and 3, causing one set of the piercing prongs 10a to be completely uncovered. It further will be noted that in the spaced or open position of the blocks, the upper block may be tilted on the upper pintles 11a of the toggle link plate as shown in dotted lines, to provide a greater angular relation and space between the blocks at one end thereof, thus facilitating attachment of the strip to the prongs at that end.

In attaching a strip of flexible abrasive material, the blocks are merely pulled apart by grasping the longitudinal edges thereof, causing the toggle link 11 to assume the position shown in Fig. 3 with the hinge pintles disposed in substantially dead center relation with the resilient fingers 12a and 13a. The strip of sandpaper or other abrasive, cut to proper length, then is folded snugly and creased about the bottom surface of the lower block 9, then folded snugly against the upper transverse edges of block 9 and one of the ends of the strip superimposed over two of the prongs 11a, usually secured at the left hand end of the block as shown in Fig. 3, with the upper block 8 tilted as shown in dotted lines, to afford more space for manipulation. The upper block may then be tilted in the opposite direction and the opposite end of the strip of sandpaper, tightly snubbed against the right hand end of the lower block 9 and impaled upon the other pair of piercing prongs 10a.

Thereafter, the two blocks may be pressed together producing a snap action by passage over dead center of the two sets of hinged pintles

11a. In such action, the tensioned resilient fingers 12a and 13a urge the flat pintles to extreme collapsed position, thereby applying a strong clamping pressure between the two blocks 8 and 9 with the result that the opposed clamping portions 8b and 9b at the end portions of the two blocks press tightly against the inwardly bent ends of strip S and firmly secure said strip independently of the prongs 10a.

10 In use of the sandpaper holding and manipulating structure, the strip S is always held flush against the bottom and ends of the lower block and will not slip or become slack with use since it is secured by efficient clamping action at both 15 ends of the strip as well as by the penetrating prongs.

In Fig. 6, a somewhat different embodiment of my invention is illustrated for particular application to the sanding of the surfaces of fragile articles.

20 In a number of States, of the United States, the law requires that the shells of eggs be abraded to remove foreign material clinging thereto. The form of my invention shown in Fig. 6 while applicable to other purposes, is particularly well adapted for manual abrasion of egg shells. To this end, the lower block 9 is provided with a pad 15 constructed of compressible cellular material such as sponge rubber and preferably having curved or rounded ends 15a. Pad 15 25 may be secured to the underside of block 9 in any suitable manner as by a cement or bonding material. In this form of the invention, the flexible abrasive sheet is superimposed below the compressible and preferably resilient pad and the ends thereof secured in the manner previously described.

30 From the foregoing description, it will be seen that I have provided a simple, inexpensive and highly efficient flexible abrasive holder and manipulator which enables a strip of abrasive to be readily installed and removed and which furnishes positive clamping action in addition to holding of the strip through penetration prongs, 35 preventing slack from occurring in the strip during use of the device.

40 It is further apparent that with my improved structure and the close cooperation between the novel connection between the blocks and the blocks and attachment brackets for my linkage, 45 the blocks never need be disconnected for attaching a strip of material and that they will be shifted longitudinally in releasing the clamping pressure to facilitate removal or attachment of the abrasive strips.

50 It will of course be understood that various changes may be made in the form, details, arrangement and proportions of the parts without departing from the scope of my invention.

55 What I claim is:

60 1. An abrasive strip holder and manipulator having in combination a pair of cooperating blocks having opposed clamping surfaces adjacent the ends thereof and mechanism for connecting said blocks together to provide clamping pressure therebetween and to also provide at will, for spaced relation between said blocks, said mechanism comprising a connecting structure adapted to be collapsed between said blocks and having terminal portions pivotally connected to 65 the inner faces of said blocks for swinging on parallel axes transversely disposed of said blocks and means for urging said connecting structure into a collapsed relationship with said blocks to thereby force the opposing clamping surfaces of 70 said blocks together.

2. An abrasive strip holder and manipulator having in combination a pair of cooperating blocks having opposed clamping surfaces adjacent the ends thereof and mechanism for connecting said blocks together to provide clamping pressure therebetween and to also provide at will, for spaced relation between said blocks and said mechanism comprising a flat toggle link having its ends pivotally connected to the inner faces of said blocks for swinging on axes transversely disposed of said blocks and for collapsing between the opposed faces of said blocks and means for urging said link as said blocks are pressed together into said collapsed relationship to thereby force the opposing clamping faces of said blocks together.

3. An abrasive strip holder and manipulator having in combination a pair of cooperating blocks having opposed clamping surfaces adjacent the ends thereof and mechanism for connecting said blocks together to provide clamping pressure therebetween and to also provide at will, for spaced relation between said blocks, said mechanism comprising a flat toggle link having hinge pintles at the terminals thereof of elongated, oblong cross section and a pair of hinge attachment brackets, one secured to the inner surfaces of each of said cooperating blocks and comprising an attachment element and a resilient curved finger connected therewith serving as a fulcrum for one of the hinge pintles of said toggle link and adapted to retain said link upright in dead center position with said blocks spaced apart and to urge said blocks into clamping relationship when said link is swung past dead center relation.

4. An abrasive strip holder and manipulator having in combination a pair of cooperating opposed members forming a body, said members having opposed clamping surfaces adjacent the ends thereof and mechanism for connecting said members together at their medial portions to provide clamping pressure therebetween and to also provide at will for spaced relation between said members, said mechanism comprising a connecting structure adapted to be collapsed between said members without interference to the

clamping action of said opposed clamping surfaces and having terminal portions swingably connected to said members for swinging on parallel axes, means for urging said connecting structure into a collapsed relationship with said members to thereby force said opposing clamping surfaces together and one of said members having strip-penetrating prongs adjacent its clamping surfaces and disposed materially outwardly of the position occupied by said connecting structure in collapsed state for positioning and retaining the ends of the strip prior to said clamping action.

5. An abrasive strip holder and manipulator having in combination a pair of cooperating opposed members forming a body, said members having opposed clamping surfaces adjacent the ends thereof and mechanism for connecting said members together at their medial portions to provide clamping pressure therebetween and to also provide at will for spaced relation between said members, said mechanism comprising a connecting structure adapted to be collapsed between said members without interference to the clamping action of said opposed clamping surfaces and having terminal portions shiftably connected with said members for providing tilting and collapsing of said connecting structure relative to the opposed face of said members, said connections for said terminal portions providing means for urging said connecting structure into said collapsed relationship when said members are initially urged together from predetermined spaced relationship whereby said opposing clamping surfaces are forced together.
